CLAIM

The ornamental design for a gear cutting tool, as shown and described.

DESCRIPTION

FIG. 1 is a perspective view of a gear cutting tool.

FIG. 2 is a front elevation view thereof. A rear elevation view is identical to the front elevation view.

FIG. 3 is a left side elevation view thereof. A right side elevation view is identical to the left side elevation view.

FIG. 4 is a top plan view thereof.

FIG. 5 is a bottom plan view thereof.

FIG. 6 is a referential top plan view thereof indicating an enlarged part.

FIG. 7 is a referential bottom plan view thereof indicating an enlarged part.

FIG. 8 is an enlarged view of the portion 8' taken along the line 8-8 in FIG. 2.

FIG. 9 is an enlarged view of the portion 9 in FIG. 6; and, FIG. 10 is an enlarged view of the portion 10 in FIG. 7.

The broken lines shown in the drawings illustrate portions of the gear cutting tool that form no part of the claimed design. The dot-dash lines show an unclaimed boundary which forms no part of the claimed design. The inside portions of the dot-dash lines form no part of the claimed design.

1 Claim, 10 Drawing Sheets
